L. M. WOOLSON

HYDROCARBON MOTOR

Filed Dec. 17, 1919

Fig. 2.

Inventor:
Lionel M. Woolson

By Milton Sibbets Atty.

UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

HYDROCARBON MOTOR.

Application filed December 17, 1919. Serial No. 345,588.

To all whom it may concern:

Be it known that I, LIONEL M. WOOLSON, a citizen of the United States, and resident of Detroit, Wayne County, State of Michigan, have invented certain new and useful Improvements in Hydrocarbon Motors, of which the following is a specification.

This invention relates to hydrocarbon motors and more particularly to spark plugs for igniting a charge of combustible mixture.

Spark plugs are ordinarily used in hydrocarbon motors to ignite a charge under compression in the combustion space in the motor cylinder. For this purpose the electrodes are adjustably mounted and are usually set something less than one sixteenth of an inch apart and in order to insure the proper setting it is customary to include, in the tool kit, a gauge.

The spark plug of the present invention, is, however, designed to meet a different set of conditions than those above outlined and is for use in a combustion chamber which is under depression or suction rather than under compression and, moreover, a chamber where a substantially continuous spark is desired rather than the intermittent spark which is essential in the usual combustion chamber. For this purpose, it is desirable that a long spark be obtained and, therefore, the electrodes are set not less than one eighth of an inch apart. In view of this difference in the spacing of the electrodes it will be evident that an operator upon removing the plug would at once decide that the terminals or electrodes were not properly adjusted and would set them nearer together. To guard against such tampering and wrong adjustment the electrodes are made non-adjustable.

The invention has for its object, therefore, to provide a spark plug adapted for use in a combustion chamber in which the charge is under depression or suction.

Another object is to provide a spark plug in which the electrodes are non-adjustable with respect to each other.

Another object is to provide a spark plug in which the distance between the two electrodes cannot be readily decreased, or, in other words, in which the gap cannot be readily shortened.

Another object is to provide a device so constructed and arranged in the combustion

chamber that the spark will be formed in the path of the charge or a substantial distance away from the point of the spark plug and from the walls of the combustion chamber.

Further objects will appear as the description proceeds.

My improved spark plug was designed particularly for use in connection with a combustion heater which is utilized for heating the charge of gas drawn into the cylinder of a hydrocarbon motor. In this type of heater the gas is drawn into the combustion chamber from a suitable source of supply, the combustion chamber being connected to and provided with an exit opening leading into the intake passage of a hydrocarbon motor whereby a suction or depression is created in the heater combustion chamber by the movement of the piston in the engine cylinder. The spark plug is so constructed and arranged in the combustion chamber that the charge in passing through the chamber comes into contact with the spark and is ignited and thereby heats the intake pipe and passing into the intake pipe mixes with the mixture from the carburetor thereby heating the mixture.

One embodiment of the invention has been illustrated in the accompanying drawing, in which:

Figure 1 is a vertical sectional view, illustrating my improved spark plug mounted in a combustion heater, and

Figure 2 is an enlarged sectional view, illustrating the details of construction of the spark plug.

Referring to the drawings, a portion of the cylinder casting of a hydrocarbon motor is illustrated, the casting 10 having secured thereto an intake pipe 11 to which is secured a carburetor of any desired form, the carburetor not being illustrated since it forms no part of the present invention.

A throttle valve 12 of usual construction is mounted in the intake pipe above the mixing chamber of the carburetor, the valve being operated in the usual manner to control the passage of the mixture through the intake pipe to the motor cylinders.

A combustion heater is carried by the intake pipe, this heater comprising a chamber having a part 13 formed on the intake pipe and a part 14 secured to the part 13 and communicating therewith. The part 14 of

the chamber is provided with an inlet passage 15 which is connected by means of a conduit 16 to a suitable fuel mixing device or carburetor and the part 13 communicates 5 with the intake pipe through a passage 17, it being noted that the passage 16 is of greater area than the passage 15 first described. A needle valve 18 is threaded into the heater and regulates the size of the inlet 10 passage 15. It is desirable that the inlet passage 15 be of less capacity than the outlet passage 17 in order that the gas may always flow toward the intake pipe, since any movement of this gas in the opposite 15 direction would tend to cause a back fire into the conduit or passage 16.

It will also be noted that a cap 19 is carried by the chamber 13 above the exit opening 17, this cap having a recess therein and 20 permitting the insertion of a plug 20 in which the exit opening 17 is formed.

The ignited mixture in order to pass out 25 of the part 13 of the combustion chamber into the intake pipe takes a circuitous path which insures the complete burning of the gases before they enter the intake pipe. A screen 21 or similar device is provided in the combustion heater for breaking up the mixture just before it reaches the igniting 30 device.

From the above description it will be seen 35 that depression or suction is produced in the combustion heater when the engine is started, thereby sucking a charge of fuel into the heater, and the object of the present invention, as previously outlined, is to effectively ignite this charge and to produce a substantially continuous flame in the heater chamber.

40 The spark plug by means of which this object is attained is illustrated in detail in Fig. 2, and it comprises a base 22 screw threaded into the wall of the combustion heater and an insulating bushing 23, preferably formed of porcelain. A conductor 23' extends through the porcelain and formed thereon or secured thereto is a centrally disposed electrode 24. The electrode and conductor are preferably cemented in place in 45 the insulating member, the opposite end of the conductor being provided with a thumb screw 25 by means of which a wire may be secured thereto. A cap 26 is carried by the base 22 and secures the insulating bushing 50 23 in place thereon. The other electrode 27 for the spark plug is arcuate in form and its ends are secured as shown at 28 to the base 22, it being understood that the base 22 is 55 formed of non-insulating or conducting material and is grounded on the wall of the combustion heater. The electrode 24 extends a substantial distance beyond the end of the insulating member 23 and also beyond the free end of the base 22, to insure 60 the formation of the spark in the path of

the gas passing through the combustion heater.

It should also be particularly noted that the radius or curvature of the arcuate electrode 27 is greater than the length of the electrode 24 and that no point on the arcuate electrode 27 is disposed nearer to the base 29 of the electrode 24 or the point of junction of the electrode 24 and the insulating member 23 than the point on electrode 70 27 located nearest to the end of electrode 24 or in alignment with said electrode. These conditions may be conveniently met by taking the center of curvature of the arcuate electrode substantially at the junction 75 of the electrode 24 with the insulating member 23. This being true it will be evident that no bending of the electrode 24 about its base would cause the end of the electrode to take a position nearer any portion of the electrode 27 than the normal distance between these two electrodes. This is important since it is desirable to have a gap of considerable length to form a long 80 spark for igniting the charge and for this reason it is desirable to guard against any tampering with the electrodes which would 85 tend to shorten the gap.

In order to enable the operator to observe 90 the operation of the combustion heater and the ignition of the mixture passing therethrough, a window 30 is provided opposite the spark.

It is believed that the operation of the 95 construction above described will be clear without further statement.

From the above description it will be seen 100 that the spark plug is adapted to fulfill the objects of the invention set forth and to produce a long spark in the path of the mixture passing through the combustion heater, the electrodes being so mounted that no tampering therewith can have the effect of shortening the spark and thereby decreasing 105 the efficiency of the plug.

110 While one specific embodiment of the invention has been described, it will be understood that modifications may be made without departing from the spirit or scope of the invention as expressed in the following 115 claims.

What I claim and desire to secure by Letters Patent is:

1. A spark plug comprising a base, an insulating member carried thereby, a fixed electrode carried by said member and projecting therefrom and an arcuate electrode having both ends fixedly carried by said base, all points on said last named electrode being equally distant from the center of the end of said insulating member.

2. A spark plug having a base and an insulating bushing, a fixed electrode carried by said bushing and having a free end projecting outwardly therefrom, and a fixed

arcuate electrode carried by said base, the radius of curvature of said arc being greater than the length of said first named electrode and the center of curvature being disposed substantially at the point of junction of said first named electrode with the bushing.

3. A spark plug comprising a base, an insulating bushing carried by said base, a

fixed electrode carried by said bushing and projecting therefrom, an arcuate electrode secured at its ends to said base, all points on the arcuate electrode being equally distant from the point of junction of the first named electrode and the insulating bushing. 10

In testimony whereof I affix my signature.
LIONEL M. WOOLSON.
